UNITED STATES PATENT OFFICE.

SIGMUND MAYER, OF CINCINNATI, OHIO, AND SAMUEL H. ALTLAND, OF INDIANAPOLIS, INDIANA.

HAT-CONFORMATOR.

SPECIFICATION forming part of Letters Patent No. 638,023, dated November 28, 1899.

Application filed April 4, 1898. Serial No. 676,487. (No model.)

To all whom it may concern:

Be it known that we, SIGMUND MAYER, residing at Cincinnati, in the county of Hamilton and State of Ohio, and SAMUEL H. ALTLAND, a resident of Indianapolis, county of Marion, and State of Indiana, citizens of the United States, have invented new and useful Improvements in Hat-Conformators, of which the following is a specification.

10 Our invention relates to certain new and useful improvements in that class of conformators in which the vertical conformator-bars automatically adjust themselves in position to accurately fit the head of the person to which 15 the apparatus is applied and in which the said bars are locked in position after adjustment, as will be hereinafter more fully set forth.

The object of this our invention is to provide means whereby the upper horizontal inwardly-inclined end portions of the conformator-bars will slide in suitable fixed guideways, to provide means for locking the top ends of said bars to retain them in position when adjusted and means for registering the 25 contour of the head of the person to which the apparatus is applied, and by the pattern so formed to rearrange the said bars in their relative positions in conformity with such pattern at any future time when so desired. 30 We attain these objects by means of the apparatus illustrated in the accompanying drawings, in which similar numerals designate like parts throughout the several views.

Figure 1 is a plan view of our apparatus. 35 Fig. 2 is a longitudinal sectional view of the same, taken through the line A B, Fig. 1. Fig. 3 is an inverted plan view of the platen-holder plate and platen. Fig. 4 is a longitudinal sectional view of the same, taken 40 through the line C D, Fig. 3. Fig. 5 represents detail broken-off section and plan views of that portion of the platen-holder plate which is engaged by the spring-catch of the paper or card holder or retainer. Fig. 6 is 45 a plan view of the paper-retainer. Fig. 7 is a longitudinal side view of the same. Fig. 8 is an inverted plan view and a longitudinal side view of the guide-piece for guiding the top inwardly-inclined end portions of the conformator-bars. Fig. 9 is a plan and a side view of the table on which the top ends of

the conformator-bars are supported. Fig. 10 is a longitudinal sectional side view of the table, paper-holder, and platen, taken through the line A B, Fig. 1, and showing the manner of assembling the same. Fig. 11 is a detail perspective broken-off view of the top portion of one of the conformator-bars; and Fig. 12 is a view of a card, showing a pattern formed by the bars or puncturing-points of 60 the conformator-bars.

The supporting-frame of the apparatus is elliptical in form and is composed of the inner rim 1, the outer rim 2, and the radiating tubular guide-pieces 3, which connect said inner and outer rims to form a single integral piece.

The conformator-bars 4, having supporting stems 7, adapted to operate in the tubular guide-pieces 3, extend vertically and are offset or stepped inwardly at their top portions a sufficient amount to cause their outer top surfaces 5 to be in alignment with their inner bottom surfaces 6, so that when the conformator is applied to any particular form of head 75 the top outer surfaces 5 of the conformator-bars 4 will represent the true size and form of such head, and to which form the hat may be applied to be formed or molded into the proper shape to conform with the contour of 80 said head to which the apparatus has been applied.

The conformator-bars 4 are slightly flared outwardly at their bottom ends 8 for the purpose of more readily applying the apparatus 85 to the head of an individual, and said conformator-bars have their top end portions curved inwardly to terminate in horizontal inwardly-inclined portions 9, which rest on the top surface of the table 10 and are held 90 in their proper positions thereon by the guiding-rim 11, in the guideways 12 of which the said end portions 9 of said bars freely slide.

The table 10 is supported in its proper position by the standards 13, which are formed 95 with the bends 14, which bends are provided for the purpose of forming a stop or gage to prevent the conformator being pressed down too far on the head to be measured. The said standards are removably and adjustably secured at their bottom ends to the lugs 15 100 secured at their bottom ends to the lugs 15^a, screwed on

said standards above and beneath said lugs, and the top ends of said standards are screwed into the table 10 or otherwise firmly secured thereto.

- 5 The table 10 is elliptical in form and has its central portion 16 elevated to an extent equal to the thickness of the ends 9 of the conformator-bars 4. The guide-rim 11 is firmly secured to said table 10 by suitable se-
10 curing-screws and is provided with the hinge-lugs 17 and the eyebolt-lugs 18, between and to which said eyebolt 19 is pivoted. The platen-plate 20 has its under side dished, and in this dished or hollow portion is secured a
15 platen or pad of paper composition, rubber, or other suitable pliable composition capable of being punctured by the pin-points 21 of the conformator-bars 4. The platen-plate 20 is hinged on the lugs 17 and is provided with
20 the bifurcated lug 22, between the bifurcations of which the eyebolt 19 is adapted to pass, and by the thumb-nut 23 of which latter bolt the said platen-plate 20 is clamped to the table 10. The paper-holder 24 is formed
25 of a thin pliable material—such as sheet-steel, brass, or aluminium—and is provided with the hinge-lugs 25^a, which are adapted to fit between the lugs 17 and the lugs 25 and to swing on the same hinge-pin or hinge-center,
30 and the said holder is provided with the spring-catches 26, which are adapted to engage the rounded edges 27 of the platen-holder plate between the lugs 22 and the lugs 28.
35 An elastic band 29, which may be of rubber, or it may be a coiled-wire spring, and is preferably made removable or detachable from the conformator-bars 4 by means of a suitable hook-and-eye connection, encircles
40 said bars 4 and is provided for the purpose of simultaneously moving said bars inwardly or toward the central portion of the supporting frame or rim and to automatically adjust said bars to conform to any profile of head.
45 We will now proceed to describe the application of our invention and the manner of using the same.
- The thumb-screw 19 is first disengaged from the platen-lugs 22 and the platen-holder plate 50 20 is swung upwardly till the platen thereof is out of contact with any of the perforating bars or pins 21. The recording-card 30, which is to be perforated to form the pattern, is placed against the platen and clamped
55 against the surface of the same by means of the paper-holder 24, which is pressed to close against the said platen to hold said record-paper 30 in its proper position. The conformator is now applied to the head of a per-
60 son required to be fitted and the bars 4 automatically adjust themselves to the contour of the head, no matter how irregular the form of the same may be. The platen-plate 20 is now pressed down in place till the bars or

pins 21 penetrate completely through the card 65 30 and perforate the surface of the said platen, by which latter means of engagement the bars 4 are locked in place. Before removing the conformator from the head to which it is applied the thumb-screw 19 is caused to secure 70 the plate-platen 20 in its closed position. The conformator is now ready to be removed, and a hat may be now blocked or molded to the form or mold in the usual and well-known manner by applying the said hat to the mold 75 formed by the top portions 5 of the conformator-bars 4 and by the application of heat and needs no description.

When it is required to furnish a hat to fit a certain head the form of which has been 80 previously recorded, the corresponding card or pattern is placed on the table 10 and the bars 4 are each alternately set with their barbs or pins 21 entering the perforations previously formed in the pattern, after which proceeding 85 the paper-holder 24 is closed and secured in this position to lock said bars 4 in position.

To facilitate the quick adjustment of the bars, which must be done by taking them one at a time, the encircling elastic band 29 is 90 preferably removed. It is also preferable to remove said band after having taken a pattern and before removing said pattern from the platen in order that the bars or pins 21 do not tear or otherwise injure the form of 95 the pattern formed.

Having thus fully described this our invention, what we claim as new and useful, and desire to cover by Letters Patent of the United States therefor, is—

In a hat-conformator, a supporting-frame of elliptic form, composed of an inner and an outer ring with a series of radial tubular guide-pieces connecting same, a series of conformator-bars provided near their lower ends with supporting-stems adapted to operate in the tubular guides aforesaid, a table provided with standards having means for adjustably connecting same with the supporting-frame, a rim having radial guides to receive the upper bent ends of the conformator-bars, upwardly-projecting puncturing-bars on said bars, a plate-platen and a paper-holder with means for securing the parts together, substantially as set forth.

In testimony whereof we have hereunto set our hands in the presence of the subscribing witnesses.

SIGMUND MAYER.

SAMUEL H. ALTLAND.
